 United Shoe Machinery Corporation, Paterson,
 N. J., a corporation of New Jersey

Application December 20, 1937, Serial No. 180,701

22 Claims. (Cl. 112—61)

The present invention relates to shoe sewing machines and more particularly to presser-foot operating mechanisms therefor.

One object of the present invention is to provide a simple and positively operating presser-foot mechanism by which the presser-foot is clamped upon and released from the work during each work feeding and stitch forming cycle of the machine, and by which a predetermined clamping or squeezing pressure may be applied to the work regardless of variations in the thickness of the work.

Another object of the present invention is to provide simple and efficient means for lifting the presser-foot from the work at the completion of a sewing operation to permit removal of the work and to place the parts in proper position for reception of a new piece of work.

With these objects in view the present invention comprises a machine including the improved presser-foot mechanism hereinafter described and particularly defined in the claims. The presser-foot mechanism illustrated in the drawings is designed primarily for use in the outsole shoe sewing machine disclosed in my pending application Serial No. 10,621, filed March 12, 1935, and all of the parts of the machine herein illustrated and not specifically described are the same in construction, arrangement, and operation as the corresponding parts of the machine disclosed in said application.

In the accompanying drawings Fig. 1 is an elevation partly in section of the presser-foot and operating mechanism therefor, with the parts in running position; Fig. 2 is a view similar to Fig. 1 showing the parts when the machine is stopped; Fig. 3 is a plan view of the parts shown in Figs. 1 and 2; Fig. 4 is a side elevation on an enlarged scale of the presser-foot and associated devices; Figs. 5 and 6 are views similar to Fig. 4 showing the parts in different positions; and Fig. 7 is a section on line 7—7 of Fig. 6.

The illustrated embodiment of the present invention comprises a presser-foot 8 secured to a lever 10 which is pivoted at 12 on an arm or bracket 14 secured to a reciprocating feed slide or carriage 16. Cooperating with the presser-foot is a work support 18 which is secured to the arm 14. Connected with a rod 20 depending from the feed slide is an arm or link 22 which, as described in my co-pending application Serial No. 10,621, filed March 12, 1935, forms one arm of a toggle by which the feed slide is reciprocated. The work, which is indicated diagrammatically at 24 in Fig. 1, is engaged between the presser-

foot and work support. The stitch forming mechanisms including a curved needle and awl are operated through openings in the presser-foot and work support on the arc indicated in dot-and-dash lines in Fig. 4.

The presser-foot is pulled yieldingly toward the work by a spring 26 secured at one end of the lever 10 and at the other end to an arm 28 pivotally mounted on the slide and adjustable by means of a bolt 30 which bears against the under side of the arm 14. For the purpose of applying to the work a squeezing pressure in addition to that afforded by the spring 26, there is provided a toggle mechanism comprising two arms 32 and 34 which are pivoted together on a stud 36. The arm 32 is pivoted on the rear of the presser-foot lever 10 at 38 and the lower end of the toggle arm 34 is pivoted at 40 on a sector-shaped plate 42 which in turn is journaled on a stud 44 carried by the feed slide. The stud 36 which forms the pivotal connection between the two toggle arms 32 and 34 is connected by a ball and socket joint 46 with a rod 48 by which the toggle is operated. The sector 42 is wedge-shaped at its periphery, as indicated at 50, to be engaged by a locking or braking shoe 52 by which the plate may be held from movement. When not locked by the shoe 52, the sector 42 merely floats on its pivot, and any movement of the toggle will merely oscillate the sector without affecting the presser-foot. If the plate is locked by the shoe 52, the motion of the toggle is communicated directly to the presser-foot lever 10. Thus with the plate locked, the presser-foot may be actuated to press or squeeze the work by straightening the toggle, as shown in Fig. 4, or to lift the presser-foot clear of the work by breaking the toggle, as shown in Fig. 5. In the operation of the machine, the sector 42 is held locked during the greater part of the cycle, and is only momentarily released to permit the presser-foot to be brought into yielding engagement with the work by the spring 26, as will hereinafter be described in detail.

The mechanism for operating the presser-foot toggle comprises the rod 48 which at its rear end is connected by a ball and socket joint 54 with an arm 56 having a hub 58 secured on a rock shaft 60. Also secured on the shaft 60 is a depending arm 62 having a slot 64 in which is adjustably secured one end of a link 66. The slot 64 provides for adjustment of the motion of the toggle. The link 66 is connected to a bell crank 68 journaled on a stud 70 and having an arm provided with a cam follower 72 received in a cam groove 55

74 of a presser-foot operating cam 76 on the cam shaft 77. As shown in Fig. 1, the cam follower 72 is in its extreme left-hand position whereby through the connections above described the toggle arms 32 and 34 are straightened (Fig. 4) to apply squeezing pressure to the work by the presser-foot. This is the position of the parts during feed of the work. After about 30 degrees motion of the cam shaft from the position of Fig. 10 1, the cam follower 72 is moved to the right by the portion indicated at *a* of the cam, thereby operating through the above-described connections to break the toggle to the position of Fig. 5, whereby the presser-foot is lifted clear of the work. Before describing further the operation of the lift cam, the connections for operating the lock will next be described.

The presser-foot lock comprises the wedge-shaped peripheral portion 50 of the sector 42 and the braking or locking shoe 52 which, as shown in Fig. 5, is shaped to engage tightly with the wedge 50. The shoe is pivotally mounted on a pin 78 which extends outwardly from, but eccentric to, a rock shaft 80 journaled in a bracket 82 on the feed slide. The construction is such that counter-clockwise rotation of the rock shaft 80 as viewed in Figs. 1 and 2, moves the shoe into braking engagement with the sector (Fig. 1) and clockwise rotation moves the shoe out of engagement with the sector (Fig. 2). Secured to the rock shaft 80 is an arm 90 having a stud 92 connected by a ball and socket joint 94 with a reciprocating rod 96. As shown in Fig. 1, the rod 96 is threaded at its rear end to receive an adjustable nut 98 against which bears a boss 100 extending outwardly from an arm 102. The boss 100 has an opening sufficiently large to permit universal movement of the rod 96 to accommodate the lateral motion of the feed slide. The 40 boss is yieldingly pressed against the nut 98 by a spring 104 retained on the rod by a nut 106 whereby the spring pressure may be adjusted.

The arm 102 constitutes one arm of a bell crank pivoted on the rock shaft 80, the other arm 108 45 of the bell crank being connected by a link 110 with an arm 112 of a bell crank which is freely pivoted on a rock shaft 114, the other arm 116 of the bell crank carrying a cam follower roll 118 received in a cam groove 120 of a locking cam 50 122. As shown in Fig. 1, the locking cam groove is circular except for a short region indicated at 123 by which the cam follower 118 is moved momentarily to the left and back again. It will be seen that during movement of the follower 118 55 to the left, under the influence of the portion 123 of the cam, the rod 96 is moved to the right, as viewed in Fig. 1, thereby rocking the shaft 80 clockwise to move the braking shoe 52 away from the peripheral edge 50 of the sector plate 42. This action momentarily unlocks the presser-foot, and places the presser-foot entirely under 60 the action of the spring 26. The sector 42 adopts a position depending on the thickness of the work.

65 The operation of the parts above described will now be explained. In Figs. 1 and 4, the presser-foot is shown clamped or squeezed on the work, the locking sector being engaged by the braking shoe 52 and the toggle arms 32 and 34 being straightened. This is the position of the parts 70 during feed of the work. After about thirty degrees rotation of the cam shaft from the position of Fig. 1, the feed motion by that time having been completed, the portion *a* of the operating 75 cam groove reaches the cam follower 72, thereby

moving the follower to the right and breaking the presser-foot toggle as previously described. The sector plate still remains locked. The resulting position of the parts is shown in Fig. 5, the presser-foot being then lifted clear of the work. At this time, the back feed of the presser foot and work support is accomplished through the connection 22. After the back feeding operation, the lock 52 is released by engagement of the portion 123 of the locking cam with the locking cam follower 118. This momentary release frees the presser-foot and permits it to be pulled into yielding engagement with the work by the spring 26. In the short interval when the brake shoe is released, the presser-foot toggle is partially straightened by virtue of the fact that a portion *b* of the operating cam groove 74 arrives at the cam follower 72, thereby moving the follower slightly to the left. This movement of the toggle does not affect the presser-foot which is then unlocked but simply resets the toggle in preparation for the squeezing pressure which is to be applied shortly afterward. This position of the parts is shown in Fig. 6, the lock being off and the toggle being in a position intermediate 20 to its straightened and wide-open positions. At this time the sector 42 has assumed a position depending on the thickness of the work. A slight further rotation of the cam shaft moves the locking cam follower 118 to the right, thereby moving the brake shoe 52 into engagement with the periphery of the sector plate 42. After a short further rotation of the cam shaft, the portion *c* of the cam arrives at the cam follower 72, moving the follower to its extreme left position, which 30 is the same as that indicated in Fig. 1. This again straightens the toggle and brings the parts to the position shown in Fig. 4, namely, that in which the work is clamped or squeezed between the presser-foot and the work support. This position of the parts is retained until the portion *a* of the cam 76 again acts on the follower 72, a distance of nearly three-quarters of a revolution during a part of which the work feed is again effected.

The presser-foot locking mechanism, as above described, operates to apply to the work a definite squeezing or clamping pressure which is independent of variations in the thickness of the work. During the period in which the presser-foot is unlocked, the presser-foot and the sector assume positions determined by the work thickness, and thereafter the definite motion of the toggle results in the application of the same squeezing pressure, regardless of how the work may vary in thickness. This feature is important, since the work should be clamped under a definite predetermined pressure sufficient to hold the work during the feeding and stitch forming cycles, but preferably below the pressure at which 50 the work will be marred. Furthermore, the presser foot is always lifted a definite distance above the work for the back feeding operation. These results are attained in the present invention by simple and positively acting devices of 55 small weight, which may be satisfactorily operated at the necessary high speed of modern sewing machines.

The machine is provided with means for automatically lifting the presser-foot from the work 70 at the completion of a sewing operation to release the work and to place the parts in readiness for receiving a new piece of work. The releasing means is connected with the starting and stopping cams of the machine which are of the same 75

character as described in my co-pending application above referred to and which will be hereinafter briefly described.

The releasing means comprises a lifting lever 130, the end of which overlies the toggle link 32 at its pivotal connection 38 with the presser-foot lever 10. The lever 130 is secured to a rock shaft 132 journaled in a bracket 134 extending upwardly from the machine frame. The lever 130 is held during the stitching operation in its upper or inactive position by a spring 136 connected between the rear end of the lever and the bracket. When the lever is depressed, as shown in Fig. 2, it engages the link 32 and acts in a direction to lift the presser-foot. Slightly before the lever 130 acts to lift the presser-foot, it is necessary to release the brake shoe 52 from the sector 42 and to this end, there is also connected to the rock shaft 132, a release lever 138 having at its end a cam roll 140 to engage a cam 142 depending from the rock shaft 88. The rock shaft 88, as previously described, carries the eccentric pin 78 on which the brake shoe 52 is mounted so that clockwise movement of the cam 142 by the roller 140, as viewed in Figs. 1 and 2, releases the brake shoe and thereby permits the lever 130 to depress the presser-foot lever and the whole toggle assembly. The rotation of the rock shaft 88 by the cam 142 pulls the actuating rod 96 to the right and this action is permitted by the spring 104 which is compressed as shown in Fig. 2.

The connections between the levers 130 and 138 and the starting and stopping cam include a lever 146 which is also secured to the rock shaft 132. The lever 146 has a curved cam surface 148 and at its extreme end a flat portion 150. The cam surface is engaged by a roller on one arm 152 of a three-arm lever which is pivoted on a fixed part of the machine at 154. The second arm 156 of the lever forms one link of a toggle of which the other link 158 is connected to an arm 160 secured to the rock shaft 114. The third arm 162 of the three-arm lever is connected by a link 164 with the starting and stopping lever. Secured to the frame of the machine is a bracket 166 having adjustable limit bolts 168 and 170 to engage the arms 152 and 162 respectively and thereby to limit the motion of the three-arm lever in either direction.

The starting and stopping lever comprises a bell crank pivoted on the shaft 78 and having two arms 172 and 174 which are in different planes. The arm 172 has a stopping cam follower 176 adapted to be engaged by the stopping cam 178 and the arm 174 has a starting cam follower 180 to be engaged by a starting cam 182. The starting and stopping cams are mounted on a hub splined to the cam shaft and arranged for movement along the cam shaft by a yoked arm 184 secured to a rod 186 which is connected to the foot operated treadle. By means of the yoked arm 184, either the stopping cam 178 may be brought into the plane of its follower 176 or the starting cam 182 may be brought into the plane of its follower 180. The conditions for stopping are shown in Fig. 2, wherein the cam has thrown the follower 176 to the right, thereby turning the arms 152, 156 and 162 in a counter-clockwise direction against the limit stop 170. This action straightens the toggle 156, 158, thereby rocking the rock shaft 114 counter-clockwise. The shaft 114 is a control shaft which, as described in my co-pending application, operates to disconnect from the driving mechanism the several actuating mechanisms for the needle and awl, the take-

up, the looper, and other thread manipulating and work feeding devices of the machine, in a manner to bring all such parts to rest in predetermined positions. By virtue of the inertia of the parts and the straightening of the toggle, the follower 176 is thrown clear of the cam 178. The counter-clockwise motion of the arm 152 lifts the cam arm 146 and thereby depresses the release arms 130 and 138 to lift the presser-foot into the position of Fig. 2, as heretofore described.

The arm 146 remains supported by the engagement of the arm 152 with the flat surface 150. The cam shaft may continue to rotate for several revolutions, but in doing so, it merely operates the toggle cam to break and straighten the presser-foot toggle. The toggle is entirely ineffective since the presser foot is then held in raised position.

To reset the parts for a subsequent sewing operation, the treadle is operated to move the yoked arm 184 in such a manner as to place the starting cam 182 in the plane of its follower 180. When the follower is engaged by the cam, the arm 174 is moved down into the position of Fig. 1, thereby rocking the three-arm lever 152, 156, 162 clockwise against the limit stop 168. As a consequence of this action, the toggle 158 is broken, thereby rocking the control shaft 114 clockwise to reconnect the various thread manipulating and feeding devices with the driving mechanism. The cam follower 180 is thrown clear of the cam 182. The clockwise motion of the arm 152 brings its end under the curved portion of the cam arm 146, thereby permitting the lifting and release levers 130 and 138 to be raised into their upper or inactive positions by the spring 136, as shown in Fig. 1. From a comparison of Figs. 1 and 2 it will be observed that the presser foot release lever 130 will move out of engagement with the presser foot lever before the roller 140 on the lever 138 is disengaged from the cam 142 which controls the operation of the locking shoe. Accordingly, the presser foot is immediately drawn into engagement with the new work by the spring 26 at a time when the presser foot toggle is straightened. This action is permitted because the sector 42 is then free, but immediately thereafter the cam 142 is released and the sector is locked. On the first engagement of the presser foot with the new work, there is no provision for applying squeezing pressure in addition to the pressure afforded by the spring 26, but none is necessary because no work feeding motion is accomplished at that time. Fig. 1 shows the relative positions of the parts immediately after operation of the starting cam and it will be seen that the toggle is shortly to be broken to lift the presser foot in preparation for the back feeding motion. After the first back feed, and until the stopping cam again operates, the presser-foot is under the control of the spring 26 and the presser-foot toggle for the normal sewing operation, as previously described.

The nature and scope of the invention having been indicated, and a specific form of the invention having been described, what is claimed is:

1. A shoe sewing machine having, in combination, a presser-foot, means for moving the presser-foot yieldingly into engagement with the work, a presser-foot lock including a floating member movable with the presser-foot to a position determined by the thickness of the work, means for locking the floating member, a toggle connected with the presser-foot, and means for operating the toggle when the floating member

is locked to squeeze the work and to lift the presser-foot clear of the work.

2. A shoe sewing machine having, in combination, a presser-foot, a presser-foot lever, a presser-foot lock including a pivoted floating member, a toggle connected between the presser-foot lever and the floating member, means for locking the floating member, and a toggle actuating mechanism operating when the floating member is locked to straighten the toggle to squeeze the work and to break the toggle to lift the presser-foot clear of the work.

3. A shoe sewing machine having, in combination, a presser-foot, means for moving the presser-foot yieldingly into engagement with the work, a presser-foot lock including a floating sector movable with the presser-foot to a position determined by the thickness of the work, means for locking the floating sector, and means for operating the presser-foot when the floating sector is locked to squeeze the work and to lift the presser-foot clear of the work.

4. A shoe sewing machine having, in combination, a presser-foot, a presser-foot lever, a presser-foot lock including a pivoted floating sector, a toggle having two links, one of which is connected with the presser-foot lever and the other with the floating sector, means for moving the presser-foot yieldingly into engagement with the work and acting to set the sector in a position determined by the thickness of the work, means for locking the sector, and toggle actuating means operating when the sector is locked to squeeze the work and to lift the presser-foot clear of the work.

5. A shoe sewing machine having, in combination, a presser-foot, means for moving the presser-foot yieldingly into engagement with the work, a presser-foot lock including a pivoted floating sector, connections between the presser-foot and the sector to move the sector to a position determined by the thickness of the work, a locking shoe for the sector, mechanism for engaging the locking shoe with the sector, and means operating when the sector is locked to operate the presser-foot to squeeze the work and to lift the presser-foot clear of the work.

6. A shoe sewing machine having, in combination, a presser-foot, means for moving the presser-foot yieldingly into engagement with the work, a presser-foot lock including a pivoted floating sector, connections between the presser-foot and the sector to move the sector to a position determined by the thickness of the work, a locking shoe, an eccentric mounting for the locking shoe, and means for operating the eccentric mounting to move the locking shoe into or out of engagement with the sector.

7. A shoe sewing machine having, in combination, a presser-foot, a presser-foot lever, a presser-foot lock including a floating member, a toggle having arms connected with the presser-foot lever and the floating member, means for locking the floating member during the greater part of the cycle of operation of the machine and for momentarily unlocking the floating member at one point in the cycle, a spring for yieldingly moving the presser-foot into engagement with the work when the floating member is unlocked, and actuating means for the toggle to set the toggle in a predetermined position when the floating member is unlocked, to clamp the presser-foot on the work immediately after the floating member is locked, and thereafter to lift the presser-

foot clear of the work while the floating member remains locked.

8. A shoe sewing machine having, in combination, a presser-foot, a presser-foot lever, a presser-foot lock including a pivoted sector and a locking shoe to engage the periphery of the sector, a toggle having arms connected to the presser-foot lever and the sector, means for locking the sector during the greater part of the cycle of operation of the machine and for momentarily unlocking the sector at one point in the cycle, a spring for yieldingly moving the presser-foot into engagement with the work when the sector is unlocked, and actuating means for the toggle to set the toggle in a predetermined position when the sector is unlocked, to clamp the presser-foot on the work immediately after the sector is locked and thereafter to lift the presser-foot clear of the work while the sector remains locked.

9. A shoe sewing machine having, in combination, a presser-foot, a presser-foot lever, a presser-foot lock including a pivoted sector, operating means for the presser-foot connected with the sector, a locking shoe cooperating with the periphery of the sector, and means for moving the shoe into or out of engagement with the sector.

10. A shoe sewing machine having, in combination, a presser-foot, a presser-foot lever, a presser-foot lock, means for operating the presser-foot lock to lock and release the presser-foot with relation to the work periodically during a sewing operation, stopping devices, a normally inactive lifting lever associated with the presser-foot lever, a presser-foot lock release member, and means operated by the stopping devices to actuate the lock release member and the lifting lever to raise the presser-foot from the work.

11. A shoe sewing machine having, in combination, a presser-foot, a presser-foot lever, a presser-foot lock, means for operating the presser-foot lock to lock and release the presser-foot with relation to the work periodically during a sewing operation, stopping devices, a lifting lever normally out of engagement with the presser-foot lever, and means operated by the stopping devices to actuate the lifting lever to raise the presser-foot, said means having provision for releasing the presser-foot lock.

12. A shoe sewing machine having, in combination, a presser-foot, a presser-foot lock, a lock operating member to lock and release the presser-foot periodically during a sewing operation, the member having a yielding connection to permit independent release of the lock, a normally inactive lifting lever associated with the presser-foot, a stopping cam, and connections from the stopping cam to the lifting lever and the lock to release the presser-foot and raise it from the work.

13. A shoe sewing machine having, in combination, a presser-foot, a presser-foot lever, a presser-foot lock, a normally inactive lifting lever associated with the presser-foot, a starting and stopping lever, and connections from the starting and stopping lever to the lifting lever and the presser-foot lock to release the presser-foot and to raise the presser-foot.

14. A shoe sewing machine having, in combination, a presser-foot, a presser-foot lock, a presser-foot lifting lever, a lock release lever, an operating arm for simultaneously operating the lifting lever and the lock release lever, starting and stopping devices, and connections therefrom to the operating arm.

15. A shoe sewing machine having, in combination,

tion, a presser-foot, a presser-foot lock, a presser-foot lifting lever, a lock release lever, an operating arm for simultaneously operating the lifting lever and the lock release lever, a starting and stopping lever, and connections between the starting and stopping lever and the operating arm.

16. A shoe sewing machine having, in combination, a presser-foot, a presser-foot lock, a presser-foot lifting lever, a lock release lever, an operating arm for simultaneously operating the lifting lever and the lock release lever, the operating arm having a cam surface, starting and stopping devices, and connections therefrom to the cam surface of the operating arm.

17. A shoe sewing machine having, in combination, a presser-foot, a presser-foot lock including a pivoted sector and a shoe movable into and out of engagement therewith, means for normally moving the shoe periodically with relation to the sector during a sewing operation, an independent lock releasing lever, a normally inactive presser-foot lifting lever, an operating arm for the lock releasing lever and the presser-foot lifting lever, starting and stopping devices, and connections therefrom to the operating arm.

18. A shoe sewing machine having, in combination, a presser-foot, a presser-foot lever, a presser-foot lock including a pivoted sector, operating means for the presser-foot connected with the sector, a locking shoe cooperating with the periphery of the sector, means for periodically moving the shoe into and out of engagement with the sector, independent releasing means for moving the shoe out of engagement with the sector, a normally inactive presser-foot lifting lever, stopping devices, and connections from the stopping devices to the releasing means and the lifting lever.

19. A shoe sewing machine having, in combination, a presser-foot, means for moving the presser-foot yieldingly into engagement with the work, a presser-foot lock including a pivoted floating sector, connections between the presser-foot and the sector to move the sector to a position determined by the thickness of the work, a locking

shoe, an eccentric mounting for the locking shoe, means associated with the eccentric mounting to move the locking shoe periodically into and out of engagement with the sector, independent releasing means associated with the eccentric mounting for moving the shoe out of engagement with the sector, a normally inactive lifting lever associated with the presser-foot, stopping devices, and connections between the stopping devices and the releasing means and lifting lever.

20. A shoe sewing machine having, in combination, a presser-foot, a presser-foot lock, a presser-foot operating cam, connections between the cam and the presser-foot to move the presser-foot periodically with relation to the work, a locking cam, connections between the locking cam and the lock to operate the lock periodically in timed relation with the presser-foot, a presser-foot lifting lever and a lock release to unlock and lift the presser-foot independently of the presser-foot operating cam and the locking cam.

21. A shoe sewing machine having, in combination, a presser-foot, a presser-foot lock, a lock operating member, a presser-foot locking cam, connections between the cam and the lock operating member to lock and release the presser-foot periodically, a stopping cam, connections between the stopping cam and the lock to release the lock, the lock operating member having yielding means to permit release of the lock independently of the operation of the stopping cam, and means controlled by the stopping cam for lifting the presser-foot.

22. A shoe sewing machine having, in combination, a presser-foot, a pivoted presser-foot lever, means for operating the presser-foot in a normal work holding and feeding cycle, a lifting lever overlying the presser-foot lever and out of engagement therewith during the normal cycle, stopping devices, and connections from the stopping devices and the lifting lever to move the lifting lever into engagement with the presser-foot lever to lift the presser-foot.

BERNARD T. LEVEQUE. 45
